DESIGN FOR A GAME BOARD

Charles C. Groesbeck, Los Angeles, Calif.

Application February 3, 1941, Serial No. 98,682

Term of patent 14 years

To all whom it may concern:

Be it known that I, Charles C. Groesbeck, a citizen of the United States, residing at Los Angeles, in the county of Los Angeles, State of California, have invented a new, original, and ornamental Design for a Game Board, of which the following is a specification, reference being had to the accompanying drawing, forming part thereof, in which:

Fig. 1 is a top plan view of a game board, showing my new design; and,

Fig. 2 is an edge view thereof.

The parallel vertical lines designate the color red, while the cross-parallel lines designate the color black.

I claim:

The ornamental design for a game board, substantially as shown and described.

CHARLES C. GROESBECK.
